UNITED STATES PATENT OFFICE.

WILLIAM H. LESLIE, OF TORONTO, ONTARIO, CANADA.

DESIGN FOR A COMBINED RADIO LOUD SPEAKER AND LAMP.

Application filed August 20, 1925. Serial No. 14,530. Term of patent 3½ years.

To all whom it may concern:

Be it known that I, WILLIAM H. LESLIE, a subject of the King of Great Britain, residing at the city of Toronto, in the county of York, Province of Ontario, Canada, have invented a new, original, and ornamental Design for a Combined Radio Loud Speaker and Lamp, of which the following is a specification, reference being had to the ac-

companying drawings, forming part thereof, in which—

Fig. 1 is a plan view;

Fig. 2 a rear elevation;

Fig. 3 a perspective view of the same.

I claim:

The ornamental design for a combined radio loud speaker and lamp, as shown.

WILLIAM H. LESLIE.
